UNITED STATES PATENT OFFICE.

FRANKLIN E. JORDAN, OF OAKLAND, CALIFORNIA.

BANK.

936,780.

Specification of Letters Patent. Patented Oct. 12, 1909.

Application filed December 11, 1908. Serial No. 467,067.

To all whom it may concern:

Be it known that I, FRANKLIN E. JORDAN, a citizen of the United States, residing at Oakland, in the county of Alameda and 5 State of California, have invented new and useful Improvements in Banks, of which the following is a specification.

This invention relates to banks, and more particularly to those adapted to be carried 10 in the pocket, and has for an object to provide a bank of this character with novel means for removably mounting one head of the bank to walls of the body portion of the bank.

15 A further object of this invention is to provide, together with novel key actuated means for releasing one head of the bank, novel and effective means for automatically closing the coin inlet passage.

20 Other objects and advantages will be apparent as the nature of the invention is better set forth, and it will be understood that changes within the scope of the claims may be resorted to without departing from the 25 spirit of the invention.

In the drawing, forming a portion of this specification and in which like numerals of reference indicate similar parts in the several views:—Figure 1 is a vertical section 30 through the bank. Fig. 2 is a view similar to Fig. 1 taken on the line at right angles thereto. Fig. 3 is a view of the upper portion of the bank showing the manner of engaging the key with the cam-shaped dog.

35 Fig. 4 is a top plan view of the escutcheon. Fig. 5 is a bottom plan view of the bracket beneath the escutcheon. Fig. 6 is a plan view of the cam-shaped locking dog. Fig. 7 is a plan view of the bracket upon which 40 the locking dog is mounted. Fig. 8 is a plan view of the key actuated means for holding the locking dog in its adjusted position.

45 Referring now more particularly to the drawing, there is shown a bank 1 comprising a receptacle having substantially parallel side walls 2 and curved end walls 3. The receptacle, at one end, is provided with a fixed head 4 provided with a longitudinally 50 extending coin inlet passage 5 which may be of any desired shape and length to receive coins of various denominations. Inwardly of the passage 5, the head 4 is provided with a bracket consisting of a flat plate 6 having parallel spaced longitudinally 55

extending side flanges 7 for a purpose to presently appear. The plate 6 is provided at the ends thereof with feet 8 attached in any suitable manner to the head 4. The plate 6 is provided with a longitudinally extending passage 9 disposed directly in line with the passage 5 formed in the head 4 and located in spaced parallel relation thereto. Spherical elements 10 are located between the plate 6 and the head 4 and are disposed in parallel rows which extend longitudinally of the said head 4 and which are engaged by an endless leaf spring 11 having parallel portions 12 arranged directly within the flanges 7 of the plate 6, and these portions 70 12 are connected to each other by curved end portions 13 located outwardly of the feet 8 as clearly shown in Fig. 1 of the drawing. It will be seen that the portions 12 of the said endless leaf springs serve normally to hold 75 the spherical elements engaged with each other thus closing the coin inlet passage 5 and the passage 9 formed in the plate 6 providing effective means for preventing the discharge of coins from the receptacle, but 80 providing effective and novel means for permitting the entrance of coins. It will be seen that upon shoving a coin into the slot 5 it will tend to move the spherical elements away from each other. 85

The receptacle 1 is provided at its end opposite the head 4 with a head 14 which will be hereinafter described as a removable head. This head carries thereupon, approximately, at the center thereof, an escutcheon 90 15 rotatably mounted in any suitable manner. The escutcheon is provided with an irregular shaped passage 16 adapted to align with a similar passage 17 formed in a bracket plate 18 secured beneath the head 14. A bracket 19 is located beneath the plate 18 and comprises a horizontally disposed portion 20, and vertical parallel spaced legs 21 secured in any suitable manner to the head 14. The portion 20 of the bracket 19 100 is provided with a centrally located passage 22 which receives a pin 23 upon which is mounted a cam-shaped locking dog 24 provided longitudinally of its length with oppositely disposed passages 25, and transversely of the said locking dog there is shown oppositely disposed passages 26. All of the said passages 25 and 26 are arranged concentric with the said pin 23. 105

A key actuated keeper is shown at 27 and 110

is formed from suitable spring material and comprises an arm 28 and a leg 29 which may be secured in any suitable manner to the head 14. The keeper 27 has its arm 28 forked as shown at 30 to provide oppositely disposed spaced portions 31 which carry at their outer ends upwardly directed pins or studs 32.

Adjacent to the head 14, the walls of the receptacle are pressed outwardly to form a bead 33 disposed in line with the cam-shaped dog 24.

By providing the keeper 27 it will be seen that the pins or studs 32 may be engaged with either series of passages 25 and 26. Assuming the pins or studs 32 to be engaged with the passages 26 it will readily appear that the locking dog is held out of engagement with the bead 33, as the width 20 of the said dog is approximately the same as the distance between the spaced walls 2 of the receptacle.

A key is shown at 34 in full lines in Fig. 3 of the drawing and comprises a shank 35 having a contracted neck 36 from which depends a head 37 having downwardly extending spaced fingers 38. The key is corrugated longitudinally so that it will conform to the irregular passage or slot 16 formed in the escutcheon. It is obvious that the key 34 may be inserted through the head 14 so that the fingers 38 may be pressed into either series of passages 25 or 26, and by pressing downwardly on the key the fingers 38 by their engagement with the studs or pins 32 will press the same downwardly so that they become disengaged with the locking dog. After this operation it will appear that by rotating the key, the locking 40 dog consequently will be rotated, and when the shank 35 of the key lies transversely of the head 14, the dog 24 at its ends will be engaged with portions of the bead in the walls 2 of the receptacle to hold the head 45 effectively engaged or locked to the receptacle.

I claim:—

1. A bank comprising a receptacle having a coin inlet passage, a head removably engaged with the receptacle, a rotatable element carried by the head adapted for locking engagement with walls of the receptacle,

and a keeper for holding the element against rotation.

2. A bank comprising a receptacle having a coin receiving passage at one end, a head for said receptacle a key actuated cam-shaped dog carried by the head adapted for locking engagement with walls of the receptacle, a keeper adapted for locking engagement with the dog, and a key for releasing the keeper and rotating the dog.

3. A bank comprising a receptacle having a coin receiving passage at one end, a head removably engaged with the receptacle, a locking dog carried by the head for engaging walls of the receptacle and provided with a plurality of oppositely disposed series of passages, a spring pressed keeper for holding the dog in its adjusted position and adapted to be engaged in the said series of passages, and a key for rotating the dog and releasing the keeper therefrom.

4. A bank comprising a receptacle having a coin receiving passage, a head having an escutcheon, a rotatable locking dog carried by the head adapted for locking engagement with walls of the receptacle, and a key adapted to be inserted through the escutcheon and engaged with the dog for engaging or disengaging the same from the walls of the receptacle.

5. A bank of the class described comprising a receptacle having a coin receiving passage at one end, a head removably engaged with the receptacle, a locking dog carried by the head adapted to be rotated and frictionally engaged with walls of the receptacle and provided with a plurality of oppositely disposed series of passages; a spring pressed keeper for holding the dog in its adjusted position and adapted to be engaged in the said series of passages for holding the dog against rotation, and a key adapted to engage the spring pressed keeper and move the same into an inoperative position to allow the dog to be disengaged from the walls of the receptacle.

In testimony whereof I affix my signature in presence of two witnesses.

FRANKLIN E. JORDAN.
